UNITED STATES PATENT OFFICE.

EPPA H. RYON, OF WALTHAM, MASSACHUSETTS, ASSIGNOR TO CROMPTON & KNOWLES
LOOM WORKS, A CORPORATION OF MASSACHUSETTS,

FILLING DETECTOR OR FEELER FOR WEFT-REPLENISHING LOOMS.

989,429.

Specification of Letters Patent. Patented Apr. 11, 1911.

Application filed July 9, 1910. Serial No. 571,129.

To all whom it may concern:

Be it known that I, EPPA H. RYON, a citizen of the United States, residing at Waltham, in the county of Middlesex and State 5 of Massachusetts, have invented certain new and useful Improvements in Filling Detectors or Feelers for Weft-Replenishing Looms, of which the following is a specification.

10 My invention relates to a filling detector or feeler for a weft replenishing loom of the type shown and described in Letters Patent of the United States, No. 972,722. Said filling detector or feeler comprises a feeler slide 15 or member, which on the forward movement of the lay is yieldingly held against the filling on the bobbin, and moves therewith a certain distance toward the front of the loom, as the lay advances, to cause the 20 pivot point of an operating lever of the replenishing mechanism to be withdrawn, or moved backward, and an angle lever or second member, which is pivotally mounted on the first mentioned member, and is adapted 25 to engage with the filling on the bobbin. Until the substantial or practical exhaustion of filling is reached, said two members move in unison. Upon the substantial or practical exhaustion of filling on the bobbin in the 30 active shuttle, when the first mentioned member engages the bobbin, there will not be a sufficient amount of filling on the bobbin to hold the engaging end of the second member or angle lever, and said angle lever will 35 rock or move on its pivotal support, and a connection to a second lever causes said angle lever to remain in its inoperative position, and act to withdraw the pivot point of the operating lever of the weft 40 replenishing mechanism, which causes a bobbin to drop from its compartment to the discharging end of the magazine, all as fully described in said Letters Patent No. 972,722, above referred to.

45 The object of my present invention is to improve upon the construction of the filling detector or feeler above referred to, which comprises two members, one member a slide, and the other member an angle lever pivoted 50 within the slide, and more particularly to have the second member or angle lever adjustably secured on the first member or slide, so that its engaging point may be moved toward or away from the filling on the 55 bobbin, to cause it to engage with the filling

on the bobbin more or less, according to the quality or nature of the filling. The engaging end of the second member or angle lever is detachably connected, and preferably has a toothed or serrated engaging edge. 60

My invention consists in certain novel features of construction of my improvements as will be hereinafter fully described.

I have only shown in the drawing detached parts of a filling detector or feeler of the type above referred to, with my improvements applied thereto, sufficient to enable those skilled in the art to understand the construction and operation thereof. 65

Referring to the drawing:—Figure 1 is a side view of the filling detector or feeler, and a shuttle with a bobbin therein, (the shuttle and bobbin are shown in section,) with my improvements combined therewith, looking in the direction of arrow *a*, Fig. 2. Fig. 2 is a plan view of the parts shown in Fig. 1, 70 looking in the direction of arrow *b*, same figure. The shuttle and bobbin are not shown in this figure. Fig. 3 shows the front end of the filling detector or feeler shown in Fig. 2, detached, and the angle lever or second member of the feeler in its opposite adjusted position. Fig. 4 is, on an enlarged scale, a section, on line 4, 4, Fig. 3, looking in the direction of arrow *c*, same figure. 75

In the accompanying drawing, 1 is a stand secured to the loom side, not shown. A stud 2 on the stand 1 has a bushing, not shown, secured thereon by a nut 3, to adjustably receive the feeler bed 4, which is fastened by a screw bolt 5, and rests at its front end on an adjustable bolt 6. The feeler bed 4 is preferably grooved on its upper portion to loosely receive the feeler slide 7, which is held thereon by a cap 8 secured by screws 8'. The feeler slide 7, which forms one member of the filling detector or feeler mechanism, is preferably made of sheet metal, and is hollow throughout its central portion, and has the engaging end 7', which is preferably of wedge shape, and may be detachable from the main slide 7, and is in this instance secured within the inner end thereof by rivets 9. The end 7' of the slide 7 is adapted to engage the filling 10 on the bobbin 11 in the shuttle 12, see Fig. 1. 90

A lug or extension 7" on the upper side of the slide 7, has a wire or rod 13 secured thereto at one end, and at its other end said rod or wire 13 extends through a boss 8" 105

on the cap 8. A helically coiled expansion spring 14 encircles the rod or wire 13, and bears at one end against the lug 7", and at its other end against the boss 8", and acts 5 to yieldingly move the slide 7 forward, or toward the bobbin 11, to engage the filling 10 thereon. An adjusting screw 15, turning in a threaded hole in the boss 8" on the cap 8, limits the forward movement of the 10 slide 7.

Within the hollow part of the slide 7 is located the second member of the filling detector or feeler, comprising in this instance an angle lever 16, which is pivotally 15 mounted within the slide 7. On one arm of the angle lever 16 is the engaging end 16', having a serrated or toothed edge 16''. The engaging end 16' is preferably made separate from the arm of the angle lever, and of vulcanized fiber or other suitable material, and detachably secured by rivets 17 within the hollow end of the angle lever 16. The other 20 arm of the angle lever 16 is pivotally connected to one end of a rod or wire 18. The 25 other end of said rod or wire 18 is pivotally connected to the upper end of an upright lever 19, which has its hub 19' fast on a shaft 20, see Fig. 1. The shaft 20 is loosely mounted in bearings 1', 1', on the stand 1, 30 see Fig. 2.

A helically coiled torsion spring 21 encircles the shaft 20, and has one end connected to a bearing 1', and its other end connected to a collar 22, secured by a screw 22" on the 35 shaft 20. The torsion spring 21 acts to cause the rotation of the shaft 20, and the movement of the lever 19 toward the right, and through the rod or wire 18, causes the movement of the angle lever 16 on its 40 pivotal support, when the engaging end 7' of the slide 7 engages the filling on the bobbin, and is moved backward toward the front of the loom. In case there is not a sufficient amount of filling on the bobbin to hold the 45 engaging edge 16'' on the lever 16 in its normal stationary position, said end will move away from the end 7' of the slide 7, and through the rod or wire 18 will leave the upright lever 19 at rest. On the opposite 50 end of the shaft 20 is secured the hub 23' on an upright lever 23; the upper end of said lever 23 is pivotally connected with the horizontally extending rod 24, which has its inner end loosely guided in a boss 1^a on 55 the stand 1. The forward end of the rod 24 extends into an opening or slotted portion 1^b, see Fig. 1, and is adapted to form the pivot point for the end of an operating lever of the selecting mechanism of the magazine, not shown, and fully shown and described in said Letters Patent No. 972,722, 60 above referred to.

All of the above mentioned parts, except the construction of the angle lever 16, may 65 be of the usual and well known construc-

tion, and as shown and described in said patent.

I will now describe my improvements.

The angle lever 16, or the second member of the filling detector or feeler, which is adapted to engage with the filling on the bobbin, is, as above stated, provided with an engaging end 16', preferably made of fiber, which is preferably made separate from the angle lever 16, and riveted or otherwise suitably secured within the end of said lever. The engaging end 16' as above stated, has its edge preferably toothed or serrated, to enter between the winds of filling on the bobbin. The hub 16''' of the angle lever 16 is loosely mounted on a bushing 25, see Fig. 4, which has an eccentrically located bore or opening therethrough, into which extends a bolt 26 having flattened sides, see Figs. 2, and 3, which prevents the bolt 26 from turning within the bushing 25, and causes said bushing to turn with said bolt. The bolt 26 has on one end a screw-head, and on its other end a nut 27. An indicator handle 28 is secured at one end on the bolt 26, and has its other end 28' upturned to form an engaging end. By means of the handle 28, the bolt 26 is turned, and with it the bushing 25, which is the pivot support of the angle lever 16. The rotation of the 95 bushing 25 will vary the position of the pivot point of the lever 16, to move the engaging end 16' of said lever outward to its extreme position, as shown in Fig. 2, or inward to its extreme position, as shown in 100 Fig. 3, or to any intermediate position, according to the amount of rotation of the bushing 25. In order to rotate the bushing 25 it will be necessary to loosen the nut 27 on the bolt 26, and after the desired adjustment of the engaging end 16' of the angle lever 16 is obtained, then said nut 27 is tightened to hold the angle lever 16, and its engaging end 16' in its adjusted position.

The object of making the engaging end of the angle lever 16 adjustable, relative to the engaging end 7' on the slide 7, is to vary the position of said engaging end 16', according to the quality or size of the filling on the bobbin, so as to obtain better results and less waste of filling.

It will be understood that the details of construction of my improvements may be varied if desired.

Having thus described my invention, what 120 I claim as new and desire to secure by Letters Patent is:—

1. In a filling feeler for looms, a member to engage the filling on the bobbin in the active shuttle, a second member to coöperate 125 with said first mentioned member, and having a movement in the direction of the length of the bobbin, and one of said members being adjustable relative to the other toward and away from the bobbin.

2. In a filling feeler for looms, a member to engage the filling on the bobbin in the active shuttle, a second member to coöperate with said first mentioned member and having a pivotal movement in the direction of the length of the bobbin, one of said members being adjustable relative to the other toward and away from the bobbin, and means for adjusting said member and holding said member in its adjusted position.

3. In a filling feeler for looms, a member to engage the filling on the bobbin in the active shuttle, a second member to coöperate with said first mentioned member, said second member adjustable with respect to said first mentioned member, toward and away from the bobbin, and a device to indicate the

position of one of said members with respect to the other member.

4. In a filling feeler for looms, a member to engage the filling on the bobbin in the active shuttle, a second member to coöperate with said first mentioned member, one of said members adjustable relative to the other, toward and away from the bobbin, and means for adjusting said member, said means comprising a bushing, a bolt passing therethrough, and an indicator movable with said bushing.

EPPA H. RYON.
